UNITED STATES PATENT OFFICE

165,704

CLOCK-RADIO HOUSING

Carl W. Sundberg, Birmingham, and Montgomery Ferar, Huntington Woods, Mich., assignors to Sylvania Electric Products Inc., a corporation of Massachusetts

Application December 23, 1950, Serial No. 13,560

Term of patent 14 years

(Cl. D56—4)

To all whom it may concern:

Be it known that we, Carl W. Sundberg, a citizen of the United States of America, residing at Birmingham, in the county of Oakland, in the State of Michigan, and Montgomery Ferar, a citizen of the United States of America, residing at Huntington Woods, in the county of Oakland, in the State of Michigan, have invented a new, original, and ornamental Design for a Clock-Radio Housing, of which the following is a specification, reference being had to the accompanying drawing forming a part hereof, in which the single figure is an elevational view in perspective

of the clock-radio housing showing our new design.

What we claim is:

The ornamental design for a clock-radio housing, as shown.

CARL W. SUNDBERG.
MONTGOMERY FERAR.
